Specification for Design.

Patented Aug. 9, 1921.

Application filed March 25, 1921. Serial No. 455,657. Term of patent 14 years.

To all whom it may concern:

Be it known that I, RONALD W. Post, a citizen of the United States, residing at Mountain Lakes, in the county of Morris and State of New Jersey, have invented a new, original, and ornamental Design for a Telephone-Earpiece, of which the following is a specification, reference being had to the accompanying drawing, forming part thereof.

In the drawing, Figure 1 is a plan view of a telephone earpiece, showing my new design, and

Fig. 2 is an edge view, or view in side elevation of the earpiece shown in Fig. 1.

I claim:

The ornamental design for a telephone earpiece as shown.

In testimony whereof I have hereunto signed my name in the presence of two subscribing witnesses.

RONALD W. POST.
